[57] CLAIM

The ornamental design for the orthodontic wire holder,
as shown and described.

DESCRIPTION

FIG. 1 is a perspective view of the orthodontic wire holder showing my new design;

FIG. 2 is a top plan view thereof;

FIG. 3 is a side elevation view thereof;

FIG. 4 is an end elevation view thereof; and

FIG. 5 is a bottom plan view thereof.

The side of the orthodontic wire holder opposite to that
shown in FIG. 3 is a mirror image thereof.
